AERATOR PUMP FOR A SWIMMING POOL SPA

Lawrence E. Johnson, 25161 Via Elevado,
Dana Point, Calif. 92629

Filed May 12, 1975, Ser. No. 576,259

Term of patent 14 years

Int. Cl. D15—02

U.S. Cl. D65—1 R

FIG. 1.

FIG. 2.

FIG. 3.

FIG. 1 is an isometric view of an aerator pump for a swimming pool spa, embodying my new design;

FIG. 2 is an elevational view taken from the side opposite that shown in FIG. 1; and

FIG. 3 is a bottom plan view thereof.

I claim:

The ornamental design for an aerator pump for a swimming pool spa, substantially as shown.
